UNITED STATES PATENT OFFICE.

FREDERICK W. FULLERTON, OF ST. PAUL, MINNESOTA.

PISTOL.

1,357,393.

Specification of Letters Patent. Patented Nov. 2, 1920.

Application filed April 1, 1920. Serial No. 370,514.

To all whom it may concern:

Be it known that I, FREDERICK W. FULLERTON, a citizen of the United States, residing at St. Paul, in the county of Ramsey and State of Minnesota, have invented new and useful Improvements in Pistols, of which the following is a specification.

My invention relates to improvements in pistols.

10 The object of my invention is to provide a simple and durable pistol so designed that substantially its entire length is taken up by the barrel. By placing the firing mechanism forward of the head of the cartridge, 15 I make it possible to have an unusually long barrel and eliminate the necessity for an independent extractor by utilizing the striker for this purpose.

A further object is to provide a pistol 20 in which barrels of various lengths and calibers may be quickly and easily substituted, one for the other.

25 My preferred form is adapted for use with rim fire cartridges only, but my alternate construction is adapted for use with center fire cartridges as well.

30 In the accompanying drawings Figure 1 is a side elevation of my improved pistol partially in section, with one side of the grip removed; Fig. 2 is a detail view of the breech latch; Fig. 3 is a perspective view of the barrel; Fig. 4 is a perspective view of the preferred construction of the hammer; and Fig. 5 is a side elevation partially in section showing an alternate construction of the firing and extracting mechanism.

35 Referring to the drawings, I have used the numeral 1 to indicate the pistol barrel, 40 2 the frame, 3 the barrel retaining screw, 4 the trigger, 5 the sear, 6 the hammer, 7 a hammer cocking knob, 8 the main spring, 9 the striker, which also performs the function of an extractor, and 10 the breech latch.

45 The letter C. indicates a cartridge.

The barrel 1 (Fig. 3) is formed with a rib 11 on its under side adapted to fit into and slide in a corresponding groove in the frame 2. A slot 12 in the under surface of 50 the rib 11 is adapted to receive the end of the retaining screw 3 when the barrel 1 is in place on the frame 2. The breech end of the barrel 1 is formed above with a rounded groove 13, which is engaged by 55 the latch 10 when the barrel is in firing position, and a notch 14 in the lower edge

of the breech provides clearance for the striker 9 to impinge against the flange of the head of a cartridge C.

The barrel retaining screw 3 is threaded 60 in a tapped hole in the frame 2, its head is knurled to facilitate turning with the fingers and its upper end 17 projects into the slot 12 of the barrel.

The trigger 4 (Fig. 1) is pivoted on a 65 pintle 4^a in the frame 2 and engages the end of a finger 5^b of the sear 5, at its upper end, while a spring 4^b located near its lower end in the frame 2 tends to hold it against a surface 4^c of the frame 2. The finger 5^b 70 is formed integral with the sear 5 which is pivoted on a pin 5^a in the frame 2. The hammer 6, shown in detail in Fig. 4, has the cocking knob 7 rigidly mounted thereon and pivots about a pin 18 which passes 75 through a drilled hole 6^a in the hammer 6. The ends of said pin 18 are rigidly held in the frame 2. The hammer 6 is provided with a slightly raised and hardened surface 19 which is adapted to impinge against 80 the end of the striker 9 (Fig. 1) or, in the alternate construction shown in Fig. 5, against a firing pin 40, hereinafter described. The shank 7^a, Fig. 4, of the knob 7 passes out through the slot 7^b, Fig. 5, in 85 the frame 2. Notches 20, in the hammer 6 are adapted to be engaged by the end of the sear 5, and a spherical recess 21 is adapted to receive a ball 22 formed on the upper end of a spring rod 23 in a manner to form 90 a pivot joint between the rod 23 and the hammer 6. The upper notch 20 is engaged by the sear 5 in the full cock position of the hammer 6, and the lower notch 20 is engaged by said sear 5 when the hammer is in 95 half cock position. The spring rod 23 has an enlarged portion 24, adapted to form a stop for the upper end of the main spring 8 and the lower end of said rod fits loosely into a drilled hole 25 in a boss 26 of the 100 frame 2. The main spring 8 is coiled around the rod 23 and is held under compression between the under side of the enlarged portion 24 of the rod 23 and the upper surface of the boss 26.

105

The combination striker and extractor 9 is formed with a notch 27 through which a small pin 28 passes, and a shoulder 29 provided with a stud 30 is adapted to be engaged by one end of a coiled spring 31. The 110 upper end of the combination striker and extractor extends into the notch 14 in the bar-

- rel 1. The coiled spring 31 tends to hold the striker and extractor against a surface 32 of the frame 2 and away from the head of the cartridge C.
- 5 The breech latch 10, shown in detail in Fig. 2, caps a projection 2^a of the frame 2 and pivots about a pin 33 in said projection 2^a. Said projection forms an abutment for the breech end of the barrel 1. A lip 34, (Fig. 2) adapted to conform to and engage 10 the notch 13 in the barrel 1, is made on the latch 10. A spring 35, in a recess in said projection 2^a of the frame 2 tends to hold the latch 10 in the position shown in Fig. 1, 15 and a roughened portion 10^a is adapted to be pressed forward when it is desired to disengage the lip 34 from the notch 13 in the barrel. Such pressure permits the barrel to slide forward.
- 20 In the alternate construction, shown in Fig. 5, I provide firing mechanism which is adapted for use on center fire cartridges, it being impossible to strike the percussion cap in such a cartridge from the front as hereinbefore described. A striker 36 is pivoted on a pin 37 in the projection 2^a of the frame 2, and a firing pin 40 extends from the lower end of said striker to the striking surface 19 of the hammer 6. The firing pin 40 is 25 formed with a cone shaped end 41 which normally rests in an externally threaded bushing 38. The bushing 38 is screwed into the frame 2 and forms a stop for the firing pin 40. A spring 39 is coiled around the firing pin 40 and is under compression between the cone shaped end 41 of the firing pin 40 and a shoulder 42 in the frame 2. An extractor 43, pivoted on a pin 44 in the frame 2 and having a spring 45 to hold it upward, 30 is provided in this alternate construction.
- In operation the pistol is cocked by pressing the knob 7 forward and downward. When the upper notch 20 passes the end of the sear 5, the sear, under the action of the spring 4^b, will engage said notch and hold the hammer 6 in the position shown in dotted lines in Fig. 1, against the action of the main spring 8, until the trigger 4 is pressed. When pressure is applied to the trigger 4, 45 the sear 5 is withdrawn from the notch 20 and the spring 8 throws the hammer 6 upward, bringing the surface 19 forcibly against the end of the striker 9. As the notch 28 allows the striker 9 to move upward, against the action of the spring 31, this drives the point of the striker into the flange or rim of the cartridge C, thereby discharging said cartridge. The breech is 50 opened and the discharged cartridge case extracted by pressing the latch 10 and pulling the barrel 1 forward to the position shown in dotted lines in Fig. 1. As this is done, the point of the striker being embedded in the flange of the empty cartridge case, the case 55 is withdrawn from the chamber of the bore

and falls or can be easily removed from the end of the striker. The end of the screw 3 coming against the end of the slot 12 forms a stop when the breech is opened. Another cartridge may now be inserted in the chamber and the barrel slid back until the latch 10 again engages the notch 13 to hold the barrel in firing position. When the barrel 1 is returned to the firing position with a new cartridge in the chamber, the head of the cartridge, coming against the projecting point of the striker 9, forces the upper end of the said striker downward against the action of the spring 31, while the striker pivots about the pin 28.

The operation of the alternate construction shown in Fig. 5 is identical with that just described as far as the operation of the barrel, trigger, sear and hammer is concerned, but when the trigger is pressed the surface 19 on the hammer 6 impinges against the cone shaped end 41 of the firing pin 40, moving said pin to the right and upward (as shown in Fig. 5) compressing the spring 39, forcing the striker 36 to pivot about the pin 37 and driving the pointed end of said striker into the head of the cartridge C thereby firing the pistol.

The barrel 1 can be removed by merely unscrewing the screw 3, releasing the latch 10 and sliding the barrel forward until the rib 17 becomes disengaged from the groove in the frame 2. This facilitates the interchange of one barrel for another.

Having described my invention what I claim as new and desire to protect by Letters Patent is:

1. A pistol having a frame and a barrel mounted on said frame, a stop for said barrel at the breech end of said frame, a latch adapted to engage said barrel in firing position, a striker arranged to impinge against the forward side of the flange of a cartridge, a rearwardly acting hammer adapted to impinge against said striker and means for actuating said hammer.

2. In a pistol, the combination of a frame, a barrel mounted on said frame and having a chamber adapted to receive a cartridge, the breech end of said barrel having a notch arranged to allow access to the forward side of the flange of the cartridge in said chamber and a striker slidable and tiltable in said frame adapted to impinge against the cartridge in said chamber through said notch in said barrel.

3. In a pistol, a frame, a grip on said frame, a barrel slidable longitudinally on said frame and projecting over the heel of the grip, a chamber for a cartridge in the breech of said barrel, a striker arranged to impinge against the cap of a cartridge in said chamber and a rearwardly acting hammer in front of said breech arranged to actuate said striker.

4. In pistol, the combination of a frame and a barrel, slideable longitudinally on said frame, having a chamber adapted to receive a cartridge, a rib on said barrel, a groove in said frame formed to receive said rib to hold said barrel on said frame, the breech end of said barrel being formed with a notch arranged to allow access to the forward side of the flange of a cartridge in said chamber and a striker slideable and tilttable in said frame adapted to impinge against a cartridge in said chamber through said notch in said barrel. 45
5. A pistol having a frame and a barrel, slideable longitudinally on said frame, having a chamber adapted to receive a cartridge, a stop for said barrel at the breech end of said frame, a latch pivotally mounted on said stop and adapted to engage said barrel in firing position, a spring mounted in said frame to hold said latch in engagement with said barrel and rearwardly acting firing mechanism adapted to impinge against the percussion cap of said cartridge. 50
- 20 6. A pistol having a frame and a barrel on said frame, a projection on said frame to close the breech end of said barrel, a latch pivotally mounted on said projection and adapted to engage said barrel in firing position, a striker adapted to impinge against the forward side of the flange of a cartridge, a rearwardly striking hammer adapted to impinge against said striker and means for actuating said hammer. 55
- 25 7. A pistol having a frame and a barrel slideable longitudinally on said frame, a projection at the breech end of said frame to close the breech of said barrel, a latch pivotally mounted on said projection and adapted to engage said barrel in firing position, a screw in said frame, a slot in said barrel engaging said screw to limit the move- 60
- ment of said barrel, a combination striker and extractor formed and arranged to impinge against the forward side of the flange of a cartridge, a rearwardly striking hammer adapted to hit said combination striker and extractor and means for actuating said hammer. 65
8. In a pistol, the combination of a frame and barrel slideable longitudinally on said frame and having a chamber adapted to receive a cartridge, a rib on said barrel, a groove in said frame formed to slidably engage said rib and hold said barrel on said frame, a notch in the breech end of said barrel, a striker slideable in said frame and arranged to strike a cartridge in said chamber through said notch in said barrel, a slot in said barrel and a screw positioned in said frame to enter said slot and limit longitudinal movement of said barrel. 70
9. A pistol having a frame and a barrel slideable longitudinally on said frame, a stop for said barrel at the breech of said frame, a latch pivotally mounted on said stop and adapted to engage said barrel in firing position, a spring mounted in said frame to hold said latch in engagement with said barrel, a rearwardly acting hammer pivoted in said frame, a striker slideable in said frame, a sear to engage and release said hammer, a finger on said sear and a trigger to engage said finger and actuate said sear. 75
10. In a pistol, a frame, a barrel mounted on said frame, a chamber to receive a cartridge in the breech of said barrel, a striker arranged to impinge against the firing point of a cartridge in said chamber and a hammer forward of the breech of said barrel arranged to actuate said striker. 80
- In testimony whereof, I have hereunto subscribed my name to this specification.
- FREDERICK W. FULLERTON.
